UNITED STATES PATENT OFFICE.

WILLIAM A. TUCKER, OF NEW YORK, N. Y.

CAPSULE-MACHINE.

SPECIFICATION forming part of Letters Patent No. 328,623, dated October 20, 1885.

Application filed April 10, 1884. Serial No. 127,235. (No model.)

To all whom it may concern:

Be it known that I, WILLIAM A. TUCKER, of the city of New York, in the county and State of New York, have invented a new 5 Capsule-Mold-Oiling Machine, of which the following is a specification, reference being had to the accompanying drawings, forming part of the same, in which—

Figure 1 is a side elevation of a machine 10 embodying my invention. Fig. 2 is a detail drawing of a portion of said machine. Fig. 3 is a plan of said machine. Fig. 4 is a vertical section of the same on line $z z$, Fig. 3. Figs. 5 and 6 are vertical sections of the same 15 respectively on lines $x x$ and $y y$, Fig. 3, and Figs. 7 to 12, inclusive, are detail views of separate parts of the machine, particularly described hereinafter.

The purpose of my invention is the cleaning 20 and oiling preparatory to the molding of capsules thereon of a series of capsule mold-pins fixed in a plate as ordinarily arranged for molding capsules to be cut or trimmed in capsule-cutting machines commonly in use. 25 This purpose I accomplish by bringing into contact with the mold-pins a strip or belt of flexible elastic material carrying the oil, looping the same upon the pins, first on one side and then on the other, and, while the oiling-belt is thus looped upon the pins, rubbing 30 the same back and forth on the pins.

I will proceed to describe a machine in which the said operations may be conveniently performed and mechanical motive power employed therefor.

The frame on which the working parts of the machine are mounted consists of two side plates, A A', connected at their ends by suitable cross-bars, B B'. (See Fig. 1, Sheet 1.) 40 In the said plates are wide openings C C', (see Fig. 5, Sheet 4,) into which to slide vertically therein are fitted plates D D'. (See same figure.) On the inner faces of these plates, at their upper and lower edges, are 45 formed inwardly-projecting ribs or flanges $d d' d'' d'''$, which extend across the faces of the said plates and some distance beyond the side edges of the same, as seen in Figs. 7 and 12 on Sheet 5.

50 $a a' a'' a'''$ (see Fig. 5, Sheet 4) are guide-plates secured to the inner faces of the frame-plates A A', with their inner edges projecting over

the upper and lower edges of the openings C C', thus furnishing ways or bearings against which the inner faces of the flanges on the 55 plates D D' bear and slide.

E (see Fig. 4, Sheet 3) is a vertical plate, in which are fixed the pins or studs b , (see same figure,) which carry the oiling devices, as hereinafter described. On the side edges of 60 this plate are formed guide-plates $c c'$, Fig. 5, Sheet 4, extending laterally on either side of said plate E, at right angles to its opposite faces.

A side edge view of E, and an outer face 65 view of one of the plates c , formed thereon, is shown in Fig. 11, Sheet 5, and in Fig. 9 is shown an upper edge view of the plate E and the two guide-plates $c c'$. The said plates $c c'$ are fitted to slide horizontally between the 70 ribs or flanges $d d' d'' d'''$, and are held in place by being dovetailed at their upper and lower edges into the said ribs, as seen plainly in Fig. 5, Sheet 4. By this arrangement the vertical plate E is mounted to reciprocate horizontally 75 in the plates D D', and the latter are held and allowed to reciprocate vertically in the openings C C' in the side plates, A A', of the frame.

F, Fig. 1, Sheet 1, is a cross-bar secured to 80 the rear ends of the wing-plates $c c'$, and to this bar is jointed a pitman or connecting rod, G which is pivoted at the opposite end to a swinging lever, H, that is pivoted at e, Figs. 1 and 4, Sheets 1 and 3, in a bracket, I, secured to the frame. This lever is vibrated by means of a driving-shaft, J, and a crank-pin in the end of the said shaft, that works in a journal-box, J', fitted to slide in an opening, J'', in the lower end of the said vibrating lever. 90 The said shaft is also journaled in the bracket I, and is provided with a driving-pulley, L, and a loose pulley, L'. (See Sheet 2, Fig. 3.) By the described means a horizontally-reciprocating motion is given to the wing-plates $c c'$, and of course to the plates E. 95

K is a shaft journaled in the frame immediately over the upper edge of the plate E, and provided at either end with a crank-pin, f f', that extends from the shaft outside of the 100 frame, and pivoted on these crank-pins at their upper ends and on studs $g g'$ are connecting-bars $h h'$, by means whereof a vertical reciprocating motion is given to the plates c

c', and through them to the plate *E*. The shaft *K* is provided with a handle, *i*, by which it may be rocked by hand on its bearings to give the said reciprocating motion to the plate *E*, as seen in Figs. 2 and 3, Sheets 1 and 2. In this plate *E* are fixed a series of studs, *b*, which studs are slotted longitudinally from their outer ends throughout the projecting portions of the same. In these slots, in each line or row of the pins, as seen in Fig. 5, Sheet 4, is arranged a belt or ribbon of a suitable flexible and elastic material, (indicated in said figure by the letter *l*) which may be a loosely-woven cotton fabric of a similar texture to lamp-wicking. These ribbons or belts are to be supplied with oil in any suitable way for the lubrication of the mold-pins, as hereinafter described.

The plates *D D'* are held in their normal position midway between the top and bottom of the openings *C C'* by springs *j j' j'' j''*, one above and another below each of said plates, the convex curves of the springs resting against ledges or rabbets *k k' k'' k''* (see Figs. 7 and 8, Sheet 5) in the inner faces of the side plates, *A A'*, and the ends against the ribs *d d' d'' d'''* on the plates *D D'*, the joint action of these springs being to maintain the said plates in the position shown in Fig. 5, centrally between the upper and lower ends of the said openings *C C'*, while they may, by means of the eccentrics on *K* and the connecting-rods *h h'*, together with the plate *E*, on which they are formed, be reciprocated vertically, as before described.

M is the mold-plate, in which are fixed the mold-pins *m*, in rows corresponding in arrangement and distance apart with the studs *b* in plate *E*, there being provided one more row each way of the studs *b* than there are mold-pins, as shown in Fig. 4, Sheet 3.

N is a cross-head arranged to slide horizontally in ways *o o'*, provided in the side plates, *A A'*, of the frame. (Shown in Fig. 3, Sheet 2.)

O (see Fig. 4, Sheet 3) is a plate-holder secured against the inner face of the said cross-head *N* by fitting the lower edge into a groove formed in a rib, *n*, at the lower edge of the cross-head, and by a flange, *p*, at the upper edge, which extends over onto the upper edge of the cross-head, and is there secured by a screw-bolt passing through the flange into the cross-head. By this arrangement the said plate-holder can be conveniently connected with and detached from the cross-head. Near the lower edge of the plate-holder *O* is a cleat or stop-bar, *q*, secured thereto by a bolt, and then, there being provided a number of screw-holes in said plate-holder *O*, the position of the said stop-bar may be shifted vertically to accommodate various sizes of mold-plates, so when a mold-plate rests upon the said stop-bar the molds in the plate will be in proper position with relation to the studs in the plate *E*.

P is a rod or bar secured adjustably in the

front face of the cross-head *N*, and extending through the end of the frame *B*, with a spiral spring, *r*, placed upon it outside of the frame, 70 one end of the spring bearing against the frame, and the opposite end against a collar, *r'*. A strap or chain, *r''*, is attached at one end to the outer end of the bar *P*, and passes over a pulley, *s*, and its opposite end is attached to the foot-board *s'*, hinged to the base of the frame. By these means the said cross-head may be reciprocated horizontally in its ways, as the operator by pressing with his foot upon the foot-board will force the cross-head 80 inward toward the center of the frame against the stress of the spring *r*, and when released from the said pressure the cross-head will be forced back into the first position by the action of the said spring. 85

t is a broad spring secured centrally in the frame to a rod, *R*, fixed in the upper part of the frame, the said spring being so arranged that when the cross-head with the mold-plate *M* is driven inward toward the plate *E* the 90 said spring *t* will bear upon the upper edge of the said mold-plate *M* and hold it in place during the operation of oiling the molds, as hereinafter described.

u is a piece of thick felting or other equivalent material that is spread over and secured to the inner face of the plate *E*, the studs *b* passing through holes in the said felt. This is designed to hold the oil with which the molds are to be lubricated, and it may be saturated with the oil in any convenient manner. 95

The operation of this machine is as follows: The mold-plate carrying the molds to be oiled and cleaned being dropped into its place in the cross-head, the latter is then 105 forced toward the plate *E* by the operators pressing upon the foot-board *s'* until the ends of the molds press against the felt *u* and take up upon themselves oil from the said felt, the several rows of molds passing in between the 110 several rows of studs *b*. Then by rocking the shaft *K* the plate *E* is forced downward, thus bringing the webs or belts *l* into contact with the pins on their upper side, so as to loop the belts around the pins, as seen in Fig. 5. Then 115 reciprocating motion is communicated to the plate *E* by the means before described, and the molds are oiled and cleaned by the rubbing of the belts *l* upon the molds. Then the shaft *K* is rocked in the opposite direction, 120 whereby the plate *E* is raised vertically, and the belts are thus brought in contact with the mold-pins on their lower side while the reciprocating motion of the plate *E* is continued. The shaft *K* is then released from the hand of 125 the operator, and the plate *E* assumes its first position under the combined action of the springs *j j' j'' j'''*. The pressure is then removed from the foot-board *s'*, when the cross-head will by the stress of the spring *r* be 130 drawn back into the position shown in Fig. 4, and the mold-plate is then removed from the cross-head and another is inserted for a repetition of the operation.

What I claim as my invention, and desire to secure by Letters Patent, is—

1. The combination, with the plate E, provided with the studs b, carrying the webs l, of a mold-plate provided with the mold-pins m, constructed and arranged as and for the purpose described.

2. The combination, with the described mold-pins, and with the plate E, provided with studs b, carrying a web, l, of the felt u, or its equivalent, as and for the purpose described.

3. The combination of the plate E, carrying the lubricating-webs, the plates D D', working in elongated openings in the side frames of the machine, said plates provided with bearings for the ends of the plate E, springs, arranged as shown, to hold the plates D D' in a central position, a rock-shaft carrying crank-pins arranged above or below the plates D D', and

connections between said plates and crank-pins, as and for the purpose described.

4. The combination of the side plates, A A', of the frame, provided with the described wide openings, the plates D D', fitted into said openings to slide vertically therein, and provided with the ribs d d' d² d³, and the plate E, provided with the guide-plates c c', fitted to slide in the said ribs, as and for the purpose described.

5. The combination, with the reciprocating cross-head N, the plate-holder O, and the mold-plate M, of the spring t on a stationary part of the machine, to bear upon the top of the mold-plate when the latter is in its advanced position, as and for the purpose described.

WILLIAM A. TUCKER.
